US00D548926S

(12) **United States Design Patent** (10) **Patent No.:** **US D548,926 S**
(45) **Date of Patent:** **** Aug. 21, 2007**

(54) **IMPLEMENT FOR CONTACTING SURFACES**

(75) Inventors: **David William Schuller**, Lebanon, OH (US); **Craig Merillat Rasmussen**, Loveland, OH (US); **Brent William Mason**, West Chester, OH (US); **Anthony Piazza**, Palo Alto, CA (US); **Sally Madsen**, Mountain View, CA (US); **Elizabeth Liebert**, Menlo Park, CA (US); **Judy M. Lee**, San Francisco, CA (US)

(73) Assignee: **The Iams Company**, Dayton, OH (US)

(**) Term: **14 Years**

(21) Appl. No.: **29/270,270**

(22) Filed: **Dec. 19, 2006**

Related U.S. Application Data

(63) Continuation of application No. 29/258,683, filed on Apr. 25, 2006, now Pat. No. Des. 536,857.

(57) **CLAIM**

The ornamental design for an implement for contacting surfaces, as shown and described.

DESCRIPTION

FIG. 1 is a perspective view of an implement for contacting surfaces ornamentation showing our new design;

FIG. 2 is a bottom view thereof;

FIG. 3 is a top view;

FIG. 4 is a right side view,

FIG. 5 is a left side view thereof;

FIG. 6 is a front view; and,

FIG. 7 is a back view.

The broken lines in the drawings are for illustrative purposes only and do not form a part of the claimed design.
